(57) **CLAIM**

The ornamental design for a dispensing cap, as shown and described.

DESCRIPTION

FIG. 1 is a perspective view of a first embodiment of a dispensing cap, showing our new design;

FIG. 2 is a top view thereof;

FIG. 3 is a bottom view thereof;

FIG. 4 is a left side view, with each of the right, front, and back views being a mirror image thereof;

FIG. 5 is a perspective view of a second embodiment of a dispensing cap, showing our new design;

FIG. 6 is a top view thereof;

FIG. 7 is a bottom view thereof; and,

FIG. 8 is a left side view, with each of the right, front, and back views being a mirror image thereof.

The broken lines are shown for the purpose of illustrating parts of the article that form no part of the claimed design.

1 Claim, 6 Drawing Sheets
